UNITED STATES PATENT OFFICE.

RUDOLPH MUELLER, OF CHICAGO, ILLINOIS.

PUMP.

Application filed January 8, 1924. Serial No. 684,956.

To all whom it may concern:

Be it known that I, RUDOLPH MUELLER, a citizen of the United States, and resident of Chicago, in the county of Cook and State 5 of Illinois, have invented certain new and useful Improvements in Pumps, of which the following is a specification.

My invention relates to improvements in pumps and has special reference to pump 10 mechanism particularly adapted for pumping syrups at soda water fountains.

Pumps of this character as disclosed in United States Patents Nos. 1,072,636 and 1,247,708 issued to me September 9, 1913, 15 and November 27, 1917, respectively, and which comprise a unitary structure adapted to be removably mounted on an open topped container, have long been known.

Such unitary pump structures comprise 20 a container cover, an open topped cylinder depending from the cover and adapted to be immersed in the liquid in the container, a delivery pipe leading from the bottom of the cylinder through the cover, a piston rod 25 mounted in the cover and connected with a piston in the cylinder and normally spring held at the upper limit of its movement.

The object of my present invention is to 30 improve and simplify the construction of such structures whereby the devices can be more readily manufactured in large quantities by means of the more modern manufacturing processes, whereby the several 35 pumps can be more readily assembled with the several parts properly aligned and connected and whereby the cost of production shall be reduced.

My invention will be more readily understood by reference to the accompanying 40 drawings forming part of this specification and in which:—

Figure 1, is a side elevation, partly in 45 central vertical section of a pump structure made in accordance with my invention; and

Figures 2 and 3 are horizontal sections on the lines 2—2 and 3—3 respectively of Figure 1.

In said drawings 10 represents a cover adapted to be applied to a container in 50 which the syrup is held and which cover carries or has attached thereto the several parts of the structure so that the structure is a self contained unit capable of being placed upon or removed from a container.

The cover 10, as shown, is a flat disk 11

provided at its edge with a depending flange 12 and is preferably stamped out of sheet metal. This disk is perforated at two points, one 13 to receive a delivery pipe 14 and the other 15 to receive a member 16 in 60 which a piston rod 17 is mounted and guided.

The delivery pipe 14 has a lower end 18 which depends a suitable distance and is 65 preferably cast integrally with an open topped cylinder 19. Possibly more inventive thought has been expended in devising means for suitably, rigidly and durably connecting the cylinder with the cover than on any other part of these pumps. 70

In modern manufacturing processes, it is the aim to eliminate all special or individual fitting or aligning and to produce each part in quantities ready to be assembled into detail or part structures which are adapted to 75 be easily assembled and connected to produce the finished device. Such is one of my objects in this present instance.

For rigidly mounting the cylinder 19 upon the cover 10, I preferably make use of 80 the delivery pipe 14 as one connector, and I preferably cast with the cylinder a rod or standard 20 opposite to and extending parallel with the delivery pipe. I provide a cross connecting plate 21 having a nozzle 85 22 for receiving the upper end of the rod 20, a central opening 23 adapted to register with the opening 15 in the cover and an opening 24 for receiving the delivery pipe 14. The delivery pipe 14 has an outwardly 90 inclined delivery end or spout 25, preferably cast solid with the pipe, and this adds to the difficulty of producing the structure. The upper end of the brace rod 20 is rigidly connected to the plate 22 preferably by riveting and soldering, and for connecting the delivery pipe to the plate I provide the pipe with a rigid shoulder 26 against which I clamp the plate 21. For this clamping I make the part 27 of the delivery pipe just 95 above the shoulder 26 of somewhat enlarged diameter and screw thread it to receive a clamping nut 28, the nozzle part 25 being small enough in diameter to permit the nut 28 to slide freely onto the part 27. 105

In assembling the parts the plate 22 is first secured in position to the upper end of the brace rod 20 and then the cover 10 is entered over the nozzle 25 and slid down to place with its top 10 flat against the plate 110

21, then the nut 28 is put on and screwed down thus clamping the cover 10 and the plate 22 tightly together and against the shoulder 26 on the delivery pipe.

5 A second point of connection of the cylinder structure with the cover is necessary in order to properly withstand the strains incident to operation, and I provide this second connection in a very simple manner.

10 The member 16 which projects through the openings 15 and 23 is hollow to act as a container for a compression spring 29 which surrounds the piston rod 17 and serves to normally hold the rod and the piston 30 secured to its lower end at the upper limit of movement. The member 16 is externally threaded to receive a clamping nut 31 which is adapted to be entered upon the lower end of the member 16 and be screwed up against 20 the under surface of the plate 21.

For clamping the plate 21 and the cover 10 at this point, I provide the member 16 with a shoulder 32 spaced from the cover 10 sufficiently to provide space for an auxiliary 25 cover member 33 which is provided with an opening 34 for the member 16 and a second opening 35 for the delivery pipe. This auxiliary cover member has a depending flange 36 sufficient only in height to contact with 30 the cover 10 and provide space beneath it for the clamping nut 28. The flange extends around the opening 34, and the opening 34 fits the member 16 just below the shoulder 32 so that when the clamping nut 31 is 35 screwed home the plate 21, the cover 10 and the auxiliary cover 33 are all three tightly clamped together between the nut 31 and the shoulder 32. The piston rod 17 is provided with a shoulder 37 for contact with the lower end of the member 16 to limit the 40 upward movement of the rod and piston.

As the structure and operation of the piston rod means for adjusting its downward movement was disclosed in my said Patent 45 No. 1,072,636, except as to the novel structure described herein, it is not thought necessary to further describe this part.

It will now be seen that I have produced an exceedingly strong and light structure. 50 One which can be manufactured at a minimum of cost, and one in which no unsightly clamping nuts are exposed to view in the finished structure, one important function of the auxiliary cover plate 33 being to hide the 55 clamping nut 28.

It is to be noted that the opening 15 in the cover for the member 16 is offset from the center, the pipe 18 being outside the cylinder 19 and the brace rod 20 extending within 60 the cylinder, and that these two connecting members are substantially centered in relation to the cover. This construction assists in the rigid mounting of the cylinder on the cover, as it permits the maximum separation 65 of the two points of connection with the

cover and consequently the structure has a maximum of rigidity in relation to its simplicity of construction.

As many modifications of my invention will readily suggest themselves to one skilled 70 in the art, I do not limit or confine my invention to the specific details of construction herein shown and described except within the scope of the appended claims.

I claim:

1. In a pump of the kind described, a cover, a cylinder adapted to be arranged below the cover, a delivery pipe extending from the cylinder and through the cover, a connecting plate beneath the cover, a brace rod disposed opposite to the delivery pipe and connecting the cylinder to the connecting plate, a nut on the delivery pipe and an opposed shoulder on the delivery pipe for clamping the connecting plate and cover together, a piston in the pump cylinder, a piston rod extending through the cover and connecting plate and connected at its lower end with said piston, and means surrounding the piston rod for tightly clamping the 90 cover and connecting plate together.

2. In a pump of the kind described, a cover, a cylinder adapted to be arranged below the cover, a delivery pipe extending from the cylinder and through the cover, a connecting plate beneath the cover, a brace rod disposed opposite to the delivery pipe and connecting the cylinder to the connecting plate, a nut on the delivery pipe and an opposed shoulder on the delivery pipe for clamping the connecting plate and cover together, a piston in the pump cylinder, a piston rod extending through the cover and connecting plate and connected at its lower end with said piston, and means surrounding the piston rod for tightly clamping the 100 cover and connecting plate together. 105 member extending through the cover and connecting plate, said guide member having a shoulder and being externally threaded below the shoulder for receiving a nut for clamping the cover and connecting member 110 together at this point.

3. In a pump of the kind described, a cover, a pump cylinder below the cover, two rigid connectors extending up from the cylinder, a connecting plate below the cover, the upper end of one of said connectors being joined to said connecting plate, the other connecting member passing through both the cover and connecting plate, and means for tightly clamping said second connecting member to the cover and connecting plate and clamping the cover and connecting plate together, a piston rod guide member extending through the cover and the connecting plate arranged to retain these two members in registry, and means on said guide member for tightly clamping the cover and connecting plate together.

4. In a pump of the kind described, a cover, a cylinder dependent below the cover,

a delivery pipe rising from the cylinder and extending through the cover, a connecting plate beneath the cover, a brace rod rising from the cylinder, its upper end secured 5 rigidly to one end of the connecting plate, the delivery pipe extending through the opposite end of the connecting plate, means for clamping the delivery pipe to the cover and connecting plate, and means for doweling 10 and clamping the cover and connecting plate rigidly together at a point between the ends of the connecting plate, as and for the purpose specified.

5. In a pump of the character described, 15 a cover, a pump cylinder dependent below the cover, a delivery pipe rising from one side of its cylinder, a brace rod rising from the opposite side of the cylinder, a connecting plate arranged beneath and in contact 20 with the cover, the upper end of the brace rod connected rigidly to one end of the connecting plate, the upper end of the delivery

pipe extending through registering openings in the cover and connecting plate, a shoulder on the delivery pipe beneath the connecting 25 plate, the delivery pipe threaded above the shoulder, a nut on the delivery pipe for clamping the pipe to the cover and the connecting plate, a piston rod guide member extending through registering openings in 30 the cover and connecting plate, a shoulder on said member above the cover, a nut on lower end of said member, and an auxiliary cover plate arranged above the cover adapted to enclose the nut on the delivery pipe and provided with an opening to receive said member, said member being adapted to clamp 35 said auxiliary cover, the main cover and the connecting plate rigidly together, as and for the purpose specified.

In testimony whereof, I have hereunto set my hand, this 17th day of December, 1923.

RUDOLPH MUELLER.
